UNITED STATES PATENT OFFICE.

ALEXANDER BLAIR THAW, OF PITTSBURGH, PENNSYLVANIA.

STABILIZER FOR AEROPLANES.

1,158,333.

Specification of Letters Patent.

Patented Oct. 26, 1915.

Application filed January 24, 1913. Serial No. 743,960.

To all whom it may concern:

Be it known that I, ALEXANDER BLAIR THAW, a citizen of the United States, and a resident of Pittsburgh, in the county of Allegheny and State of Pennsylvania, have invented a new and Improved Stabilizer for Aeroplanes, of which the following is a full, clear, and exact description.

Among the principal objects which the present invention has in view are: to provide a mechanism of the character mentioned to selectively operate in accord with the list or tilt of the aeroplane by which it is carried; to provide a mechanism of the character named with a wind motor operable by the pressure of the air through which the aeroplane is passing; to provide in a machine of the character named, means operative concordant with the steering mechanism of an aeroplane, to maintain the ratio of stability at various inclinations of the aeroplane; to provide a universal stabilizer; to provide means for varying the ratio of stabilization; and to provide means for varying the ratio of stabilization relative the longitudinal and transverse dimensions of the aeroplane.

One embodiment of the present invention is shown in the accompanying drawings, in which—

Figure 1 is a sectional elevation of a stabilizer constructed in accordance with the present invention; Fig. 2 is a vertical cross section taken on the line 2—2 in Fig. 1; Fig. 3 is a plan view of the stabilizer; Fig. 4 is a detail view, on an enlarged scale and in vertical section, showing one of the electrical contact posts with which the machine is equipped; Fig. 5 is a diagrammatic view showing the electrical wiring and selective contacts for operating the various elements of the stabilizing mechanism; Fig. 6 is a diagrammatic view showing the electric wiring and selective contacts for operating the various elements of the stabilizing mechanism, constructed and arranged in accordance with a modification of the present invention; Fig. 7 is a detail view, on an enlarged scale, showing the upper fragment of a connector such as used in conjunction with the modified form of wiring shown in Fig. 6; Fig. 8 is a general view, showing an aeroplane and the present stabilizing machine as mounted in operative position thereon.

As seen in the drawings, and particularly

Fig. 8 thereof, the herein-disclosed stabilizer is connected with warping sections such as A and B, and with a levitating rudder C. Said warping sections A and B are connected to drums 14 and 15, respectively, while the levitating rudder C is operatively connected to drums 16 and 17 at the lower and upper side thereof, respectively. The drums are suitably mounted in standards 60 erected upon a base plate 18, which is suitably mounted upon one of the carrying planes of the aeroplane. The above connections are effected by cables 19, 20, 21 and 22, arranged substantially as shown in Fig. 8 of the drawings.

The drums 14 to 17 inclusive are mounted on sleeves held rigidly in standards 23, 24 and 25. As seen best in Fig. 1 of the drawings, the drums 14 and 15 are mounted each on a sleeve 26, the outer end whereof is flanged to hold the hubs 27 of said drums in bearing relation with the face of said standards 23 and 25. The central standard 24 holds two short sleeves 28, the flanged 70 ends of which hold the hubs of the drums 16 and 17 in bearing relation to the faces of the standard 24. Each of the standards mentioned is provided with a cap 29, which may be tightened to draw upon the sleeves 75 26 and 28, to hold the same rigidly in position.

The sleeves 26 and 28 are alined to form a bearing for a driven shaft 30. Mounted rigidly upon the shaft 30 is a worm wheel 90 31, with which is meshed a worm 32. The pitch of the worm and worm wheel and the ratio therebetween are varied to accommodate the amount of rotation in speed desired between the vertical driving shaft 33 95 and the shaft 30, the intention being that the shaft 30 shall rotate relatively slowly.

The shaft 33 is vertically disposed and suitably mounted in bearings in the base plate 18. The shaft is rigidly connected 100 with the worm 32, and at the lower end with a hub 34, from which are extended arms 35 supporting each at its outer extremity an anemometer cup 36. The length of the arms 35 and the number of arms and cups 36 employed may be varied to suit the conditions or desire of the owner. The air motor thus formed is relied upon to drive the shaft 33, the lower end whereof is mounted in a steady bearing 37 at the lower end of a 105 suitable tripod 38.

It will be understood that while the air

motor above described is shown in the accompanying drawings as disposed below the stabilizer herein disclosed, it may, if the design compels such an arrangement, be located at any suitable station on the aeroplane. Likewise, the disposition of the air motor may be varied so that the cups rotate in a vertical plane rather than in the horizontal as shown in the drawings. Proper transmission mechanism connecting the shaft 33 and the air motor may be employed to suit the exigencies of the design.

When using a motor such as described, the shafts 33 and 30 are continuously rotated while the machine is in flight, irrespective of the fact of the operation of the propelling motor. In other words, the shaft 30 is rotated during the gliding periods of flight of the aeroplane.

20 Mounted upon the shaft 30, to rotate therewith, are two double-faced clutches 39 and 40. Elongated feathers or splines 41 are provided, to govern said clutches when moved lengthwise of the shaft 30. This movement is imparted by clutch yoke levers 42 and 43. The ends of the yokes of the levers 42 and 43 are provided with pins to extend into grooves 44, with which said clutches are provided. The clutch levers 42 and 43 are pivotally mounted on pins 45. The lower end of each of said levers is provided with a cross bar soft iron armature 46 extending between the cores of magnets 47 and within the magnetic area thereof. The levers 42 and 43 are held centrally disposed by springs 48.

25 The magnets 47 are operated selectively, one or two of the same being energized coincidentally in accord with the tilting of the base plate 18. The various magnets are operated by a suitable battery mounted in a battery-box which is rigidly secured to the base plate 18. One leg of the circuit of each of the magnets 47 includes one of the tube caps 50. The opposite leg of the circuit of each magnet incorporates one of the tubes 51 and the mercury 52 contained therein. Each of the tubes 51 has a vertical section 53. In the normal or horizontal position of the base plate 18, the mercury 52 in each of the vertical sections 53 of the four tubes 51 is at the same level and on a level with the top of the mercury in tube 51. In this position of the base plate and mercury contained in the tubes 51, the space between said mercury and the needle 54 in each of the tube caps 50 is the same. This space may be varied to suit the desires of the aviator, to render the machine rigid or flexible in its stabilization.

30 It will be understood that when the aeroplane carrying the stabilizer is tilted in its transverse or longitudinal plane, to incline the base plate 18 until the mercury 52 in one of the vertical sections 53 makes contact

35 with the needle 54 of one of the tube caps 50,

the electric circuit is thereby established in one of the magnets 47. The energized magnet draws to it the armature 46 with which it corresponds, rocking the lever 42 or 43, as the case may be, to throw the clutch 39 70 or 40 connected therewith.

The clutches 39 and 40 are each provided on the opposite faces with truncated teeth 55, which engage the spokes of the drums 14 to 17 inclusive. It will be understood that any suitable form of clutch may be employed. The electric circuits are so arranged that the tube caps 50 transversely disposed relative the longitudinal axis of the aeroplane operate the magnets 47 to throw the levers 42 and 43 to engage the drums connected with the warping sections A and B. A further arrangement insures that the tube cap on one side of the longitudinal center of the base plate as disposed on the aeroplane, operates the magnet which affects the warping section on the same side of said longitudinal center. Likewise, the caps 50 longitudinally disposed on the plate 18 and aeroplane are incorporated in circuits operating to control the drums which are connected with the levitating rudder C, and these longitudinally-disposed caps are selectively arranged to operate the cables 21 and 22 arranged to incline the rudder C upward and downward, respectively.

35 From the foregoing, it will be seen that with the caps 50 set to govern the free tilt of the aeroplane, thereafter the warping sections A and B and the levitating rudder C will be automatically adjusted to correct the tilt of the aeroplane whenever the list extends beyond the limit set therefor, and by reason of the fact that the electric circuit is established in the proper magnet 47 to throw the clutch on the shaft 30 to engage the proper drum 14, 15, 16, or 17, to cause the same to rotate with said shaft 30, this resulting in the inclination of one or the other of said warping sections of the carrying plane or the uplifting or depression of the rudder C.

The arrangement and construction of the caps 50 and the section 53, whereby the point of contact is varied, is best seen in Fig. 4 of the drawings. The tube cap 50 is internally threaded, the threads registering with the threads of a screw nut 56, which is rigidly mounted at the upper end of the section 53 and insulated therefrom by a bushing 57 formed of any suitable insulating material.

The tube cap 50 is externally provided with a fin 58. The fin 58 extends through a groove formed in a collar 59, said collar serving as a guide for the tube cap 50 and to form an electrical contact therewith. The collar 59 is suitably mounted at the upper end of a bracket 60, the foot of which rests upon an insulating pad 61, and is provided with a binding post 62 to receive a

wire terminal 63 directly connected with one of the magnets 47, see Fig. 5 of the drawings.

The nut 56 above referred to is rigidly mounted upon a hollow shaft 64, which shaft has a bearing on the section 53 of the tube 51, and is provided at the lower end with a fixed bevel gear wheel 65. The gear wheel 65 is meshed with a mated gear wheel 66 forming one of a pair of corresponding wheels fixedly mounted upon a transmission shaft 67. The shaft 67 has bearings in the vertical edge flange of the base plate 18, and is provided at the outer side of said flange 15 with a pulley 68.

There are two shafts 67, each connecting, by means of the gears 66, the oppositely-located shafts 64 and bevel wheels 65 connected therewith. Each of the pulleys 68 is 20 operatively connected, preferably by auxiliary belt loops 69, with the controlling levers or tiller posts of the aeroplane.

A predetermined amount of slack in the auxiliary loops 69 is provided, the purpose being to permit the controlling levers, or the tiller, to be operated to a predetermined degree before the pulleys 68 and parts connected therewith are affected. The purpose in this construction is to provide 30 for lifting the needles 54 under certain operating conditions of the aeroplane, such as, for instance, when banking or turning a sharp curve. The shaft 67 and its pulley 68 which extends between the caps 50 disposed transversely in the aeroplane, is connected with the rigging for controlling the rudder for steering the aeroplane in a horizontal plane. The shaft 67 and pulley 68 for operating the longitudinally-disposed 40 caps 50 are operatively connected with the rigging for varying the levitating rudder C.

When either of the shafts 67 is rotated, it will be seen, the wheels 65 and shaft 64 connected therewith are rotated and equally rotated at opposite sides of the base plate 18. The nuts 56, being rigidly mounted on the shafts 64, are similarly rotated. The caps 50, being held against rotation by the fins 58, are lifted or depressed, as the case may 50 be, by the operation of the nuts 56.

The result of the action above set forth is that the space between the mercury 52 contained in each of the tubes 51 and in the sections 53 thereof, and the needle 54, is varied 55 to suit the above-mentioned conditions arrived at in the operation of the aeroplane. In other words, when a stabilizer is thus equipped, if the aviator desires to bank his machine, by throwing the rudder to turn a sharp curve and at the same time manually 60 manipulate the warping planes; to lift one side thereof, the corresponding shaft 67 is rotated to lift the caps 50 operatively connected therewith to increase the space between the needles 54 and the mercury con-

tained in the sections 53. By setting the rigging for controlling the aeroplane in its proper relation to the shafts 67, the same distance between the mercury and needle may be preserved when in the tilting or banking position as when in the horizontal or normal position. When thus arranged, it will be seen that during the banking, or what may be termed the "incidental" position of the aeroplane, the safety factor of varying the inclination is preserved by means of the present stabilizer, which will operate from the position set to accommodate the banking as readily as from the position set to accommodate the sailing on a level plane.

In Fig. 7 is shown a modified form of the contact terminals. The modification consists in that the sections 53 are provided with an internal screw thread at the upper end to receive a screw-threaded plug 70. The plug 70 is constructed from insulating material, and is of a length to admit of insertion or withdrawal from the section 53. Three needles 71, 72 and 73 are extended 90 through the plug 70, extending from the under surface thereof to varying degrees. When the plug is screwed into the section 53, it will be seen by reference to Fig. 7 of the drawings that the space separating the needles from the mercury 52 in each case varies.

The needles are provided with binding posts 74, 75, and 76, to which are connected terminal wires 77, 78 and 79. The wires 77, 78 and 79 connected with each of the plugs 70 are united in a common ground and electrically connected to a wiper 80. The wipers 80, 85 and 86, as seen in the diagram Fig. 6 of the drawings, are clustered about a disk 105 or wheel, which wheel is provided with an electro-conductive section 81 and a non-conductive section 82. The section 81 is connected with the terminal 83 of a battery 84. When the wheel having the sections 81 and 110 82 is rotated, the various wipers are successively placed in circuit with the battery 84. Each of the wipers is electrically connected with all of the needles 71, 72 and 73 of the same length; that is, the needles 71 in each 115 of the tube sections 53 are connected with the wiper 80. Two wipers 85 are each electrically connected with all of the needles 72. A wiper 86 is connected with all of the needles 73. Each of the tubes 51 is electrically 120 connected with one of the magnets 47, and all of the magnets are electrically connected to a return wire or ground 87. Thus, it will be seen that whenever the mercury 52 in any one of the sections 53 is floated into contact 125 with the needle 71, the circuit is completed through the magnet 47 corresponding with the particular tube 51 in which the contact is made, provided the wheel having the section 81 is turned to form contact between 130

said section and the wiper corresponding with the particular needle. In other words, if the mercury 52 is raised in the tube section 53, to contact with the needle 71, the 5 circuit will be completed through one of the magnets 47, provided the wiper 80 is in contact with the section 81 of the rotary wheel, as shown in Fig. 6 of the drawings. It will be noted in this figure that the heavy black 10 lines indicate the circuits including the needles 71, while the light lines include the circuits embodying the needles 72 and 73.

If, by the operation of the steering levers of the aeroplane, the loop 88 of the steering 15 rigging be manipulated to rotate the section 81, to contact with the wiper 86, then it will be noted that the circuits embodying the needles 71 and 72 are broken, the wipers 80 and 85 being in contact with the insulating section 82 of said wheel. The mercury 20 52 may under these conditions, rise into contact with the needles 71 and 72, without energizing the magnets 47. When, however, the mercury rises to contact with the needle 25 73, the electric circuit is completed through one of the magnets, thereby energizing the same to operate the stabilizer.

It will be noted that there are two wipers 30 85. In this manner provision is made for turning the disk or wheel having the sections 81 and 82, in either direction, to employ the needle 72 equally when banking to the right or banking to the left.

It will be observed that as the mechanism 35 above described provides for a continuously operating driving shaft and temporary engagements therewith for each of the winding drums 14 to 17 inclusive, the contact between the shaft and the drums might be continued 40 beyond the flexing limit of the ailerons or warping sections. This would necessarily result in breakage of the aeroplane or connective gearing. To avoid such a contingency, I have provided spring brushes 89, 45 which are mounted on the frame of the machine and insulated therefrom. Said brushes are connected with their respective magnets by means of wires 90. The brushes bear against the peripheries of the flanges of 50 the drums 14 to 17, respectively, which, at a certain portion are provided with an insulating section 91. The leg of the circuit from said magnets to the battery contains 55 the spring brushes 89. The operation, when thus equipped, of the drums, provides for less than a whole revolution of said drum. When, in the operation, the insulating section 91 passes under the spring brush 89, it will be seen, the circuit is broken in the magnet holding the levers 42 and 43, permitting the springs controlling said lever to retract the clutches 39 and 40 from engagement with the drum at the moment operating. The pressure of the warped or inclined section 60 or aileron immediately retracts the

drum, carrying the insulating section 91 from under the spring of the brush 89, to permit the reestablishment of the current through the magnet, with the consequent result of reengagement with the clutch, of 70 the drum, in operation. By this means, it will be seen, the mechanism is saved from the results of the drum making more than a complete revolution.

While I have herein described the stabilizer as employing a motor for operating the shaft 30, it will be understood that I may employ an electric motor, compressed air admitted to cylinders when needed, from a reservoir, or other suitable prime mover, preferably independent of the propelling power for the aeroplane.

Having thus described my invention, I claim as new and desire to secure by Letters Patent:—

1. In combination with an aeroplane having a plurality of righting members, a stabilizer, comprising a shaft; a wind motor for continuously driving said shaft; a plurality of winding devices, each operatively connected with one of said righting members; a plurality of electro-mechanically-actuated connectors for operatively connecting said shaft and said winding devices successively; and a plurality of self-leveling circuit-closers, each adapted to close the circuit of one of said connectors.

2. In combination with an aeroplane having a plurality of righting members, a stabilizer, comprising a plurality of winding members; a motor adapted to be operated by the pressure of air through which the aeroplane travels; means for temporarily connecting said motor and winding devices successively; electro-mechanically-operated clutches for connecting said motor and winding devices; and circuit-closers for actuating the mechanism controlling said clutches, said closers having columns of mercury and containers therefor, wherein the mercury relatively rises as the side of the aeroplane supporting the same is lowered.

3. A stabilizer, having a continuously-operating shaft; a plurality of winding drums mounted on said shaft; a plurality of electro-magnets for connecting said shaft and said drums; a plurality of electric circuits, each incorporating one of said magnets and an electric source; a plurality of bent mercury-containing tubes, each having a portion disposed perpendicular to the horizontal of the aeroplane, each of said tubes being incorporated in one of said circuits; a plurality of contact members, one movably mounted in each of said tubes, above the mercury therein; a plurality of mechanisms, each adapted to lift said contact member in said tube to vary the separation of said member and said mercury, in the normal position of said aeroplane; and means op-

eratively connecting said mechanisms with the controlling gear of said aeroplane.

4. In a stabilizer such as described; a plurality of electro-actuated operating mechanisms embodying normally open circuits; a plurality of bent mercury-containing tubes, said tubes being arranged in pairs and spaced apart, said pairs being disposed in perpendicular vertical planes; a plurality of inverted tubes, each telescopically arranged to cover one of said bent tubes; a contact needle mounted on each inverted tube to extend within said bent tube for immersion in the mercury therein; a plurality of rotary members mounted within said inverted

tubes; means operatively connecting said inverted tubes and rotary members to reciprocate said tubes when said members are rotated; means connecting said rotary tubes in pairs to move in unison; and means operatively connecting each of said pairs with the controlling mechanism of the aeroplane to move in predetermined relation therewith. 20

In testimony whereof I have signed my name to this specification in the presence of 25 two subscribing witnesses.

ALEXANDER BLAIR THAW.
